UNITED STATES PATENT OFFICE.

HARRY A. DAVIS, OF HOPEDALE, MASSACHUSETTS, ASSIGNEE TO DRAPER CORPORATION, OF HOPEDALE, MASSACHUSETTS, A CORPORATION OF MAINE.

SHUTTLE-FEELER THREAD PARTER AND CLAMP.

Application filed March 30, 1927. Serial No. 179,641.

This invention relates to shuttle feeler thread parters and clamps whereby on replenishment of filling the thread is parted between the cloth selvage and shuttle, and 5 the end leading to the cloth selvage is clamped and positioned for the action of the temple thread cutter.

It is now the practice to provide filling replenishing looms with means for parting 10 the thread adjacent the shuttle when in the replenishing box and to clamp the end leading to the cloth selvage so that on forward movement of the shuttle feeler the thread will be carried forward and held for the 15 action of the temple thread cutter. An instance of this type of shuttle feeler thread parter and clamp is shown in the Harry A. Davis Patent, No. 1,585,898, dated May 25, 1926, and the present invention is a further 20 development and improvement on the construction therein shown and described.

In shuttle feeler thread parters and clamps as heretofore generally constructed, the thread parting member adjacent the side of 25 the shuttle feeler rests directly against the shuttle feeler and the cooperating thread parter acts in conjunction therewith to part the thread. In such devices, also, it is usual to provide a clamp for clamping the thread 30 and as disclosed in the Davis patent above mentioned a stripper is employed for stripping the thread from the parter when the thread parter and clamp is opened.

One of the objects of the present invention 35 is to provide a shuttle feeler thread parter and clamp wherein the parting member, usually fixed, is spaced from the side of the shuttle feeler and is yieldable laterally during the thread parting operation. By thus 40 enabling the parting member adjacent the shuttle feeler to yield laterally, a more effective, sheer cut is provided when the cooperating parting member acts to part the thread. In the Davis patent above mentioned, 45 the thread stripper serves to strip the thread from the clamping members when the thread parter and clamp is opened, and the present invention seeks to improve upon the thread stripper by forming a recess in 50 the face thereof to insure freeing the thread when the thread parter and clamp is opened.

Another important feature of the present invention consists in a double grip thread parter wherein a stationary or fixed clamping member and stripper is interposed be-

tween the movable thread parter and the outer thread clamp which is connected to the movable thread parter by an articulated connection and a lock, so that on removal of the locking element, the thread parter and outer 60 thread clamp may be relatively moved to provide access either to the cutting edge of the thread parter or the clamping portion of the movable clamp.

The invention and novel features thereof 65 will best be made clear from the following description and the accompanying drawings of one good form of the double grip thread parter and clamp, it being understood that in certain aspects of the invention the novel 70 features thereof may be embodied in other forms of shuttle feeler thread parters and clamps.

In the drawings:

Fig. 1 is a perspective view of a double 75 grip thread parter and clamp, showing the outer clamping member as having been moved relatively to the parting member to provide access to the cutting edge of the parting member and the clamping face of 80 the outer clamp;

Fig. 2 is a horizontal section on an enlarged scale, showing the relation of parts 85 in their normal operating positions; and

Fig. 3 is a side elevation.

The shuttle feeler 1 may be of any usual character and, as shown in the present instance of the invention, its rearwardly extending portion is provided with the shuttle 90 engaging jaws 2 and 3, whereby, should the shuttle be not properly positioned in the box, the shuttle feeler will prevent replenishment of filling. The shuttle feeler is normally supported in position at the front of the loom and on call for replenishment of 95 filling is moved rearwardly to ascertain the position of the shuttle and carry the shuttle feeler thread parter and clamp into operating position to part and clamp the thread. The means for effecting such movement of 100 the shuttle feeler is not herein shown and described because the details thereof form no part of the present invention.

In the present instance of the invention, 105 the thread parting member adjacent the side face of the shuttle feeler is shown as stationary or fixed, and interposed between the side of the shuttle feeler and the said parting member is a spacer which provides a space along the cutting edge of the parting mem-

ber to permit lateral movement thereof during the thread parting operation.

More specifically stated, the shuttle feeler has mounted thereon the stud or pin 4, and the several parts constituting the thread parter and clamp may be held in associated relation for parting and clamping the thread by a spring washer 5 interposed between the head 6 of the bolt or pin 4 and the side of a stationary clamp and stripper 7.

The stationary thread parting member 8 has an opening 9 through which the pin or bolt 4 passes, and interposed between the side face of the shuttle feeler and the parting member 8 is a spacer or washer 10 which serves to laterally space the fixed parting member 8 from the side face of the shuttle feeler, so that the front parting or cutting portion of the stationary parter 8 may yield laterally when the cooperating parting member is moved to part the thread. Owing to the spaced relation, as indicated at 11, between the surface of the shuttle feeler and stationary parting member 8, the latter may yield laterally towards the face of the shuttle feeler during the thread parting operation. This structural condition also permits the stationary thread parter or member 8 to normally occupy a position as shown in dotted lines, Fig. 2, so that its cutting edge will laterally overlap to a slight extent the corresponding cutting edge of the cooperating cutting member 12, so that when the movable parting member 12 is moved to part the thread, a sheering action is provided, which effectively parts the thread during the thread parting operation, and at the same time the fixed parting member 8 is moved laterally by the movable parter 12 from the dotted to the full line position indicated in Fig. 2, and towards the face of the shuttle feeler.

The movable thread parting member 12 is pivotally connected to the shuttle feeler by the stud 13 extending laterally from the feeler forward of the bolt or pin 4 and constitutes the fulcrum or pivot point about which the movable thread parter turns during the thread parting operation. The movable thread parter 12 is also provided with an enlarged opening 14 through which the bolt or pin passes, so that the movable thread parter 12 may turn upon its pivotal support 13 during its opening and closing movements.

In order that the fixed thread parter 8 may be held in fixed position and in spaced relation from the side of the shuttle feeler, the forwardly extending end portion of the fixed parting member is bifurcated, as at 15, and the recess of the bifurcation engages the pin 13.

At the side of the movable thread parter 12 is the thread clamp and stripper 7 which, as shown, is mounted upon the stud or pin

4 and its bifurcated end portion 16 engages the outer portion of the pivotal stud 13, thereby holding the stationary thread clamp and stripper 7 in fixed position, in a manner substantially the same in this respect as the fixed thread parting member 8.

The stationary thread clamp and stripper 7 has its lower portion at 17 formed with a clamping surface to cooperate with the grooved clamping surface 18 of the thread parter, so that when the thread has been parted by the cooperating parting members 8 and 12, its end leading towards the cloth selvage will be clamped and moved forwardly with the shuttle feeler to position the end leading to the cloth selvage for the action of the temple thread cutter. The upper portion of the stationary clamp and stripper is provided with the forwardly extending toe 19, the front edge portion 20 of which constitutes a stripper for stripping the thread from the parter and clamp when the parter is opened.

To insure that the stripped thread will be entirely free when the thread parter and clamp is opened, the side faces 21 of the stripper are recessed or countersunk, with the result that when the thread parter and clamp are opened and the thread stripped from the clamp, the recesses 21 insure freedom of the thread, so that it will not be carried rearwardly with the shuttle feeler into the danger zone of being carried into the shed.

Associated with the movable thread parter and clamp 12 is an outer clamp 22 which is articulated to the movable thread parter 12 by a pin 23, shown in the present instance as forward of the pivotal support 13 of the movable parting member, and interposed between the side of the parting member 12 and the front end portion of the outer clamp is a filler piece 24.

In accordance with the present invention, the outer clamp 22 and the movable parting member 12 which is pivotally connected thereto by the pin 23, are normally locked together by a locking member 25, which as shown consists of a detachable pin passed through the forwardly extending portions 27 of the movable thread parter 12 and the outer clamp 22, the construction being such that when the movable thread parter 12 and the outer clamp 22 are locked together by the locking pin 25, they are moved as a unit to clamp and part the thread, and upon removal of the locking pin 25, the movable parting member 12 and the outer clamp 22 may be relatively moved about their connection 23 to provide access to the cutting edge portion of the parting member and the clamping face of the clamping member.

In the present instance of the invention, the locking pin 25 for locking the movable

thread parter and the outer clamp together for movement as a unit in parting and clamping the thread, is constituted by the parter and clamp opening pin 26, but, obviously, any removable locking member which will serve to lock the movable parting member and the outer clamp together for movement as a unit will serve the purpose.

10 The outer clamping member 22 is preferably formed as a resilient spring member which by virtue of its resiliency bears upon the outer side of the fixed parter and stripper 7.

15 The spacer 10 which serves to laterally separate the parting portion of the stationary parter from the side of the shuttle feeler is formed as a washer mounted upon the pin or stud 4 and between the stationary parter 20 8 and the side face of the shuttle feeler, but such spacer may be otherwise formed, the essential in this respect being that the parting portion of the stationary parter shall be separated laterally from the side face of 25 the shuttle feeler to permit of lateral movement thereof during the thread parting operation, and also to permit the lateral overlapping of the cutting edges of the stationary thread parter and the movable 30 thread parter to insure a sheer cut.

It may be desirable at times to provide the side face of the movable parting member 12 with scores or indentations which may cooperate with the inner side face of 35 the clamping portion 17 of the fixed clamp and stripper 7 to thereby more securely clamp the thread and hold it as strain is placed thereon when the shuttle feeler is moved to its front position.

40 From the construction described it will be obvious that the thread parter and clamp shown is of the double grip type wherein the fixed parting member 8 is laterally separated from the adjacent side face of the 45 feeler with its cutting edge slightly overlapping the cutting edge of the movable thread parter 12 to insure a sheer cut, and it will likewise be obvious that when the thread has been parted and clamped by the 50 clamping surface 18 and the outer clamp 22, and the movable thread parter and outer clamp are opened, the stripper will act to strip the thread, while the recessed portions 55 21 at the side of the stripper will insure disengagement of the thread as the shuttle feeler moves rearwardly to shuttle feeling position. During normal operation of the device, the movable thread parter 12 and the outer thread clamp 22 which is pivotally connected thereto at 23, will be locked together by the locking device 25, and when it is desired to have access to the cutting edge of the knife for sharpening purposes or to the clamping face of the outer clamp, 60 the lock 25 may be removed and the mov-

able thread parter 12 and outer clamp 22 may be relatively moved about their connection to expose the surfaces to which access is desired.

70 The opening device of the thread parter and clamp is not herein shown because it may be of any usual character now well-known and constituted to act upon the pin 26 to open the parter and clamp as the shuttle feeler moves rearwardly to shuttle feeling position ready for the parting and clamping operation. Such parting and clamping operation may be effected in any usual manner, as by a portion of the lay or 75 a part secured thereto, to act upon the front tail portions of the thread parter and clamp, but since such devices are now well-known, they are not herein shown and described. By removing the locking device 25, the outer clamping member 22 and the moveable parting member 12 may be swung into the position indicated in Fig. 1 without removal from the shuttle feeler, to thereby provide access to each of said members.

80 While the parting member 8 is shown as fixed in the illustrated form of the parter and clamp, the invention is not necessarily restricted in this respect and such parting member 8 may be otherwise contrived to cooperate with the parting member 12 in 85 parting the thread.

90 95 What is claimed is:

1. In a shuttle feeler thread parter and clamp, the combination of a fixed parting member laterally spaced from the shuttle feeler to permit lateral movement of the fixed parting member towards the side of the shuttle feeler, a clamping member, a movable thread parter and clamp mounted on the 100 shuttle feeler having a parting edge on one side and a thread clamping surface on the opposite side to cooperate with the clamping member, and a thread stripper formed as a toe extending from the clamping member 105 and having side recesses to strip and free the thread as the parter and clamp are opened.

2. In a shuttle feeler thread parter and clamp, the combination of the shuttle feeler having a parting member and a clamping member, a thread parter and clamp between the parting member and clamping member, and a thread stripper extending above the clamping surface of the clamping member 110 and having side recesses for stripping and freeing the thread as the parter and clamp are opened.

3. In a shuttle feeler thread parter and clamp, the combination of a shuttle feeler having parting and clamping members for 115 parting and clamping the thread, and a thread stripper formed as an upwardly extending toe to strip the thread from the clamping members as they are opened and provided with a recessed side surface for 120 125 130

- freeing the thread as the parting and clamping members are opened.
4. In a shuttle feeler thread parter and clamp, the combination of a shuttle feeler having parting and clamping members for parting and clamping the thread, and a thread stripper extending above the clamping surfaces of the parting and clamping members when in thread clamping position to strip the thread from the clamping surfaces as they are opened and provided with a recess at each side surface of the thread stripper for freeing the thread as the parting and clamping members are opened.
5. In a double grip shuttle feeler thread parter and clamp, the combination of a shuttle feeler having a thread parting member adjacent the side thereof and a fixed clamping member, a combined thread parter and clamp between said members, an outer clamping member, an articulating connection between the combined thread parter and clamp and outer clamping member for relative movement of said members to permit access to the cutting edge of the parter, and a locking and unlocking device for holding said members for relative movement that they may act as a unit to part and clamp the thread and for freeing them to such relative movement at will.
6. In a double grip shuttle feeler thread parter and clamp, the combination of a shuttle feeler having a thread parting member adjacent the side thereof and a fixed clamping member, a combined thread parter and clamp between said members, an outer clamping member, a pivotal connection between the combined parter and clamp and the outer clamping member that they may be relatively moved on the shuttle feeler to permit access to either, and a locking and

unlocking device for holding them from such movement that they may act together to part and clamp the thread and for unlocking them at will that they may be so relatively moved.

7. A double grip thread parter and clamp, comprising, in combination, a shuttle feeler, a movable parting member, a fixed clamping member, an outer clamping member cooperating with fixed clamping member to clamp the thread, a connection between the movable parting member and outer clamping member permitting relative movement of said members from their normal relative positions on the shuttle feeler for ready access to their cutting and clamping portions, and a locking device for locking the parting and outer clamping members together in their normal relations to cause them to move together to part and clamp the thread and for unlocking them that they may be relatively moved.

8. In a double grip shuttle feeler thread parter and clamp, the combination of a shuttle feeler having a thread parting member adjacent the side thereof and a fixed clamping member, a combined thread parter and clamp between said members, an outer clamping member, a pivotal connection between the combined parter and clamp and the outer clamping member that they may be relatively moved on the shuttle feeler to permit access to either, and a screw pin for locking said members from relative movement that they may part and clamp the thread and freeing them at will to such relative movement.

In testimony whereof, I have signed my name to this specification.

HARRY A. DAVIS.
